[57] CLAIM

The ornamental design for a one piece tamper resistant refillable rodent bait station, as shown and described.

DESCRIPTION

FIG. 1 is a side elevational view of the one piece tamper resistant refillable rodent bait station showing my new design, the view from the opposite side being a mirror image;

FIG. 2 is a top view thereof;

FIG. 3 is a left end elevational view thereof;

FIG. 4 is a right end elevational view thereof;

FIG. 5 is a bottom view thereof; and,
FIG. 6 is a vertical cross sectional view taken substantially along the line 6—6 of FIG. 2.

FIG. 4

FIG. 2

FIG. 3

FIG. 1

FIG. 5

FIG. 6
